UNITED STATES PATENT OFFICE

BENNIE N. BRUNBERG, OF PROCTOR, MINNESOTA, ASSIGNOR OF THIRTY-FIVE PER CENT TO CHARLES G. WOOD AND TWENTY PER CENT TO AXEL JOHNSON, BOTH OF PROCTOR, MINNESOTA

SWITCH

Application filed January 21, 1928. Serial No. 248,460.

This invention relates to electric switches and has special reference to a time switch whereby the switch may be thrown and not function until a predetermined lapse of time.

5 The principal object of the invention is to provide a more practical, simple, and dependable switch of this character than heretofore known.

Other objects and advantages of the invention will appear in the further description thereof.

15 Referring now to the accompanying drawings, forming part of this application, and wherein like reference characters indicate like parts:

Figure 1 is a central vertical section through the operating shaft of the switch, and

20 Figure 2 is a similar section taken at right angles to Figure 1.

1 represents a rectangularly shaped housing made of any suitable insulating material such as bakelite or the like and preferably formed into the five sided receptacle 1 provided with the removable cover or back 2. Within this receptacle is rotatably mounted the cylinder 3 having one end permanently closed and the other end open for purposes hereinafter described. This cylinder 25 upon the button controlled side is provided with the telescopic trunnion comprising the female member 5 fixed to the side of the cylinder and the male member 5 fixed to the inner face of the box or receptacle, and axially of the female member 4 is a hub-like extension 6, it being slotted diametrically, and the innermost terminus of the stem 7 of the button 8 has a projection 9 which registers within the diametrical slot in the hub 6 when 30 the stem is in position for rotating the cylinder 3. This stem is held in position by a through pin mounted within the member 5 so as to be engaged within the circumferential groove 10 about the stem 7.

45 The trunnion upon the opposite side comprises the member 11 fixed to the side of the cylinder 3 having the axis 12 extending therefrom and into the female member 13 fixed to the back or cover 2. The member 11 is also 50 provided with knobs 14 so positioned as to

register with similar depressions in the collar 15 mounted upon the female member 13 in such a manner as to hold the cylinder in vertical position when the switch is turned, and the exterior of the member 13 is squared to 55 prevent rotation of the member 15. This member or collar 15 is held normally impinging the member 11 by means of a pair of suitable leaf springs indicated at 16, one upon either side of the member 13 and carried with 60 in depressions of the collar so as not to become dislodged except when the cover 2 is removed. Thus when the cylinder 3 is rotated by the switch 8 the members 11 and 15 will separate the depth of the members 14 65 and permit of the cylinder revolving until the members 14 and 15 again register, which as is obvious will tend to hold the switch in vertical position which is essential for its proper functioning in either on or off position. 70

Within the cylinder 3 is mounted a comparatively heavy metal floating piston 17, it having an axial projection 18 which when the piston is in its lowermost position, after having assumed such by gravity when the cylinder is adjusted to the position shown in Figure 2 of the drawings, will engage the spring leaf 19 of the electric circuit through the receptacle and separate its free terminus 20 from the free terminus 21 of the opposite 75 spring leaf 22 of the circuit; the other ends of these two leaves having any desired terminal post for outside connection, those here employed being illustrated at 23.

A stop ring 24 is installed adjacent the 85 upper end of the cylinder 3 so as to properly limit the descent of the piston 17 and a suitable distance from the piston when in this position is located a relief port 25 through the wall of the cylinder so that as the piston, 90 descending in the cylinder passes such port the air admitted therethrough will permit of the piston suddenly dropping to its lowermost position indicated in Figure 2, thus more effectually and quickly opening the 95 circuit.

In the closed head of the cylinder 1 is installed an adjustment plug 26 having a needle controlled valve indicated at 27 which governs the port 28 leading into the bore of 100

the cylinder and by which adjustment plug the time required for gravitating of the piston is predetermined so that the element which is employed in the control of the switch may be varied to suit the desired circumstances.

From the foregoing it is evident that I have devised a simple and practical time switch, which may be readily assembled, and as is noted by the removal of the cover or back of the switch box the entire mechanism may be removed for repair or adjustment, and one that will doubtless function adequately for the purpose intended.

Having thus described my invention, what I claim and desire to secure by Letters Patent, is:

The combination with a time switch of the class described having a rotative cylinder and gravity piston therein for control of same, of contact points spaced adjacent the path of the cylinder and independent thereof, and means whereby when the cylinder is in one of its vertical positions the contact points will be opened by the action of the piston, and when the cylinder is in its alternative vertical position the contact points will remain closed.

In testimony whereof I affix my signature.

BENNIE N. BRUNBERG.
